United States Patent Office.

WILLIAM BOWEN, OF DAYTON, MICHIGAN.

Letters Patent No. 100,491, dated March 8, 1870; antedated March 1, 1870.

IMPROVED BED-BOTTOM.

The Schedule referred to in these Letters Patent and making part of the same.

To all whom it may concern:

Be it known that I, WILLIAM BOWEN, of Dayton, in the county of Newaygo, and State of Michigan, have invented a new and useful Improvement in Bed-Bottoms; and I do hereby declare the following to be a full, clear, and exact description of the same, reference being had to the accompanying drawings, in which—

Figure 1 is a perspective view of my invention detached from the bedstead.

Figures 2 and 3 are perspective views of the stirrup detached.

My invention relates to that class of bed-bottoms in which the slats are hung upon separate springs; and

It consists in the peculiar construction of the stirrup or cage in which the spring is supported, and by which it is attached to the loose rail of the bedstead.

That others may understand my invention perfectly, I will particularly describe it.

A A are the ordinary slats of a bed-bottom.

B B are two loose rails fitted to rest in seats at each end of the bedstead, so that by removing said loose rails the entire bed-bottom may be removed at one time.

The slats have each a slit, c, at each end through which the central loop of the stirrup passes, and by which the slat and stirrup are maintained in their proper position in regard to each other.

The stirrup, figs. 2 and 3, is made of a single rod or wire and two plates, as shown.

The rod D is bent and folded at its middle to fit the loose rail B, and from thence both parts of the rod descend a distance of several inches, and, with an oblique fold or bend, the ends return upward again.

Before being bent upward, as last described, the two perforated plates, E E, are slipped on to the rod and passed up to the central bend or fold of the same. The ends are then turned and bent, as described, and brought to the two remaining holes in the plates, so that they may be brought to the positions shown in figs. 2 and 3.

Between the plates E E the spring F is confined. The said spring may be simply placed within the cage formed by the wire D when bent in the form described; but, for additional security against displacement, I prefer to pass the two free ends of the rod through the coil of the wire, while the remaining or central parts of the same pass on the outer side of the coil, as shown.

The ends of the rod D should come in contact with the lower side of the loose rail B, and, in order to be so placed, the slits G G are made in the ends of each slat, parallel with the slits c.

The end of the slat is interposed between the upper plate E and the lower side of the loose rail B, straddling the parts of the wire D, and receiving a secure and elastic support from the stirrup and spring.

Having described my invention,

What I claim as new, is—

The stirrup composed of the wire D and plates E, substantially in the manner described, in combination with the spring F and slats A, for the purpose set forth.

WILLIAM BOWEN.
